ADJUSTABLE ARMREST

Jack A. Shaw, Long Beach, Calif.

Application October 22, 1948, Serial No. 55,890

1 Claim. (Cl. 155—113)

1

This invention relates to an adjustable arm rest for divans, sofas, couches, love seats and the like and has for its primary object to provide a swingably mounted arm rest capable of being swung downwardly from its normal upright position to provide an additional seat or to enable a person to recline in a prone position with the legs extended and without the discomfiture or inconvenience of resting the legs on the top of an arm rest.

More particularly, it is a primary object of the present invention to provide an adjustable arm rest of extremely simple construction which may be incorporated in divans, sofas and the like without material modification or additional construction expense and which is capable of being quickly and easily adjusted from a normal upright position to a substantially horizontal, extended position.

Another object of the invention is to provide an adjustable arm rest having a novel brace which is movable automatically by adjustment of the arm rest to an operative position for supporting the arm rest in an extended, substantially horizontal position or against the outer side of the arm rest when the latter is moved to its normal, upright position.

Various other objects and advantages of the invention will hereinafter become more fully apparent from the following description of the drawing, illustrating a presently preferred embodiment thereof, and wherein:

Figure 1 is a perspective view of one end of a divan or sofa shown equipped with the adjustable arm rest and illustrating the arm rest in its normal, upright position;

Figure 2 is a view similar to Figure 1 but showing the arm rest in an extended, substantially horizontal position;

Figure 3 is a sectional view taken substantially along a plane as indicated by the line 3—3 of Figure 1, and

Figure 4 is a fragmentary perspective view looking toward a rear corner of the divan or sofa.

Referring more specifically to the drawing, for the purpose of illustrating one application and use of the adjustable arm rest, designated generally 5 and comprising the invention, the numeral 6 designates generally one end of a divan or sofa of which said arm rest 5 forms a part and including a frame 7 having depending supporting legs 8 at the corners thereof and which provides a support for a cushion 9 forming the seat of the divan or sofa 6. Said divan or sofa 6 also

includes a substantially rigid back rest 10 which is likewise preferably cushioned.

The adjustable arm rest 5 which may be suitably cushioned or padded on its inner side as indicated at 11 to correspond with the seat 9 and back rest 10, has a substantially rigid bar 12 secured across its outer side and adjacent its bottom edge to which corresponding leaves of a plurality of hinges 13 are suitably fastened. The other leaves of the hinges 13 are secured to an end of the frame 7 or to the legs 8 by a conventional driven fastening for swingably supporting the adjustable arm rest 5 for swinging movement from its normal upright position of Figure 1 to an extended position, as illustrated in Figure 2. A bar or cleat 14 is secured to and extends across the outer side of the arm rest 5 adjacent its upper edge. A hook 15 is swingably mounted on a pin 16 which projects from one end of the cleat 14, said hook 15 being swingable across the outer or backside of the back rest 10 into and out of engagement with a pin 17 which projects rearwardly from the back rest 10. It will be readily apparent that the hook 15, when in engagement with the pin 17, will retain the adjustable arm rest 5 in its normal upright position of Figure 1.

A brace 18, preferably in the form of a substantially rigid plate, is connected by means of a plurality of hinges 19 to the legs 8, substantially below the hinges 13 for swingably supporting the brace 18 on the divan or sofa 6. A spring 20 is associated with the hinges 19 and arranged to urge the brace 18 upwardly and inwardly with respect to the divan 6 so that when the arm rest 5 is latched in its raised position of Figures 1 and 3, the spring 20 will retain the brace 18 in an upright position and with its upper portion bearing against the bar 12.

When it is desired to utilize the adjustable arm rest 5 as an additional seat or for reclining on the divan 6, the hook 15 is swung upwardly to disengage it from the pin 17 so that the arm rest 5 can be swung outwardly and downwardly on its hinges 13 to its extended position of Figure 2. As the arm rest 5 is swung outwardly and downwardly, it will cause the brace 18 to swing outwardly and downwardly on its hinges 19 against the action of its spring 20. In this movement of the arm rest 5, the upper free edge of the brace 18 will slide outwardly along the outer surface of the arm rest 5 until said arm rest reaches substantially a horizontal position as seen in Figure 2 at which time the outer, free edge of the brace 18 will move into engagement with the inner edge of the cleat 14 which thus forms a stop for

the brace 18 so that the brace will support the seat 9 to enable its use as an auxiliary seat or as a rest for the legs in reclining on the seat 3 of the divan. The strength of the spring 20 is insufficient to return the arm rest 5 to its raised position but when said arm rest 5 is swung upwardly and back to its position of Figures 1 and 3, the spring 20 will automatically return the brace 18 to its position of Figures 1 and 3.

Obviously, the parts 12, 14 and 18 may be made to conform in appearance to the material of the frame 7.

Various modifications and changes are contemplated and may obviously be resorted to, without departing from the spirit or scope of the invention as hereinafter defined by the appended claim.

I claim as my invention:

An adjustable arm rest for divans or couches comprising an arm rest hingedly connected along its bottom edge to an end of a couch or divan for swinging movement from a normal upright position outwardly and downwardly to substantially a horizontal position, a brace hingedly connected to an end of the divan or sofa beneath the hinged edge of the arm rest, spring means for urging said

brace upwardly and inwardly and against the outer side of the arm rest and normally supporting the arm rest in an upright position, and a cleat extending along the outer side of the upper free edge of said arm rest and engaging the free end of said brace when the brace is swung outwardly and downwardly by the outward and downward swinging movement of said arm rest for positioning the brace to support the arm rest 10 in its extended, substantially horizontal position.
